EXTRA CASING JAW FOR DRILL PIPE
TONGS

Malcolm E. Self, Eunice, N. Mex.

Application December 18, 1936, Serial No. 116,561

1 Claim. (Cl. 81—66)

This invention relates to drill pipe tongs and more particularly to the jaw elements thereof.

Heretofore, drill pipe tongs in the oil well, or other analogous arts, have been made in various

5 sizes each designed primarily for use with pipes of definite dimensions within a range of narrow limits. Thus a drill pipe tong designed for example for pipe diameters ranging from three to four and one-half inches is restricted to pipes 10 of such sizes and could not be used with pipes of greater diameters. As a result of this condition, it becomes necessary when pipes of different sizes are used to change from one pair of drill pipe tongs to another with a consignment expenditure of a great amount of time and labor. In 15 addition to this disadvantage it is also necessary to have on hand an assortment of drill pipe tongs of various sizes which is not only expensive but also requires considerable storage space and an 20 undue amount of handling.

It is accordingly the principal object of this invention to obviate all the above enumerated disadvantages by providing for use with a standard pair of drill pipe tongs of conventional design, an extra casing jaw which is so designed as to permit the insertion thereof either singly or in any desired number between the pivotally connected casing jaws of the tongs whereby the capacity of the tongs is substantially increased 25 to permit the use thereof with pipes of a diameter much greater than that for which the drill pipe tongs was normally intended.

Another object of the invention relates to the adaptable nature of the extra jaw which is so 30 designed as to permit its insertion between any two of the standard casing jaws of the tongs or between the body of the tongs and an adjacent jaw, said extra casing jaw being also adaptable for coupling together to form a pair for insertion as a unit where desired in the manner as 35 above indicated.

Other objects and advantages of the invention will become apparent as the description thereof given hereunder proceeds with reference to the 40 accompanying drawing wherein:

Fig. 1 shows in a plan view the casing jaw end of a conventional drill pipe tong in attached position to a drill pipe.

50 Fig. 2 shows in a similar plan view the casing jaw end of a conventional drill pipe tong with one inserted extra casing jaw.

Fig. 3 is a plan view similar to that of Fig. 2 showing two extra casing jaws inserted between 55 the standard jaws of the tongs.

Fig. 4 is a perspective view of the extra casing jaw.

Fig. 5 is a bottom plan view of the extra casing jaw.

Referring to Fig. 1, 10 denotes the arm of one form of conventional drill pipe tongs only the jaw carrying portion thereof being shown, said arm 10 at its forward end terminating in a jaw carrying extension 11. Pivotally mounted on the extension 11 are the inner ends of the jaw elements 12 and 13, and pivotally mounted on the outer ends of said jaw elements are the clamping jaw elements 14 and 15. The inner ends of the jaw elements 12 and 13 are bifurcated in the manner well known to provide opposed bosses 16 and 17, respectively (only the upper which are shown) and which straddle the extension 11 for pivotal connection thereto through the medium of the pivot pins or bolts 18 and 19. The outer ends of the jaw elements 12 and 13 terminate in single bosses (not shown) which fit between the opposed bosses 20 and 21 at the inner ends of the jaw elements 14 and 15 which are identical with the bosses 16 and 17, the jaw elements 12, 13 and 14, 15 being pivotally connected together through the medium of the pivot pins or bolts 22 and 23. The outer end of the jaw element 14 has pivotally connected thereto a latch element 24 provided with a head 25 adapted to have interengaging and locking relationship with the abutments 26 provided on the end of the jaw element 15 as clearly shown. Both the jaw elements 14 and 15 are provided with manipulating arms 27 and 28, respectively. Each of the jaw elements are provided with arcuate projecting clamp faces 29 which are adapted to seat on the cylindrical surface of the drill pipe 30 in clamping engagement therewith. Inasmuch as the above described parts do not constitute any part of my invention, being conventional structure, a more detailed description thereof is deemed unnecessary. The drill pipe 30 is shown in Fig. 1 with the jaw elements of the drill pipe tongs clamped thereon.

In order to utilize the tongs 10 with a drill pipe of a diameter much larger than the drill pipe 30, I have provided an extra casing jaw 32 shown in perspective in Fig. 4. This extra casing jaw is made of the same material as the jaw elements of the tongs and is bifurcated at one end to form the opposed bosses 33 and 34 which are of identical dimensions as the bosses 16, 17 and 20 and 21 of the jaw elements, and are spaced apart the required distance to receive therein either the jaw carrying extension 11 or the single boss on the outer ends of the inner jaw elements 55

12 and 13. At its other end the extra casing jaw 32 is provided with a single boss 35 which is arranged in the central longitudinal plane thereof, said single boss being of the same dimensions as 5 the single boss formed at the outer ends of the inner jaw elements 12 and 13. Between the bosses 33, 34 and 35 is the body portion of the extra casing jaw which is provided on its bottom side with an arcuate projecting clamp face 36 that extends laterally the full width of the casing jaw. 10 On its upper face the body portion of the extra casing jaw is provided with strengthening webs 37.

By virtue of the above construction the extra 15 casing jaw 32 may be inserted between any two of the jaw elements or between either of the inner jaw elements and the jaw carrying extension 11 of the tongs to increase the size or capacity thereof. Referring to Fig. 2, the extra casing 20 jaw 32 is shown inserted between the jaw elements 12 and 14 and pivotally connected thereto by the pivot pins or bolts 18 and 22; the opposed bosses 33 and 34 straddling the single boss on the forward end of the jaw element 12 and the single 25 boss 35 fitted between the opposed bosses 20 on the inner end of the outer jaw element 14. It will be observed that with the insertion of the extra casing jaw 32 the drill pipe tongs 10 will accommodate a drill pipe 31 which is of a much 30 larger diameter than the drill pipe 30.

In Fig. 3, there is shown two such extra casing jaws 32 and 32' pivotally connected together as at 40 and inserted as a unit between the jaw elements 12 and 14, being connected thereto in the 35 manner as set forth above. With the addition of two such extra casing jaws, the drill pipe tongs 10 will accommodate a drill pipe 41 of a still greater diameter.

It is to be understood that the extra casing jaw

32 may be made of any desired shape or size providing the same is insertible between the pivotal jaw element connections of the tongs. While in Figs. 2 and 3, the extra casing jaw has been shown inserted between the jaw elements 12 and 14 it is obvious that if so desired the same may be inserted between the jaw elements 13 and 15, or between the inner jaw elements 12 and 13 and the jaw carrying extension 11. In addition various different embodiments of the invention may be employed within the scope of the accompanying claim.

Having thus set forth and disclosed the nature of this invention, what is claimed is:

An extra casing jaw for insertion between a 15 pair of normally adjacent pivotally connected clamping elements of a drill pipe tong, comprising a structurally integral unit having spaced parallel wall portions, said wall portions converging at one end thereof and merging into a single 20 wall portion arranged centrally between said parallel wall portions, a laterally extending boss formed at the other end of each parallel wall portion to form an eye at each end thereof, said eyes being provided with coaxial bores, a laterally 25 extending boss formed on each side of said single wall portion and provided with an axial bore therethrough to define a single eye, said unit having a clamping portion, said clamping portion comprising parallelly extending reinforcing walls 30 in spaced relation to said parallel wall portions, each of said reinforcing walls being structurally integral with and forming an extension of a lateral boss on said parallel wall portions, and an arcuate clamping member extending transversely 35 beneath said wall portions and joining the bottoms of said parallel reinforcing walls adjacent their end edges.

MALCOLM E. SELF.
